SLIP

Sylvia Roodner, New York, N. Y.

Application May 27, 1944, Serial No. 537,680

2 Claims. (Cl. 2-73)

My invention relates to a new and improved slip.

The objects of the invention are to provide an improved slip of the form-fitting type, having the following features and characteristics:

- (a) it will automatically accommodate itself and conform to the body of the wearer;
- (b) it will not ride or hike up on the body of the wearer;
- (c) it presents a well fitting and neat garment responding to the movements of the wearer;
- (d) it has a minimum number of seams;
- (e) it has no side seams, thus reducing the possibility of tearing;
- (f) there is no tension on the seams as they are located at the front of the slip;
- (g) it has an improved bodice or brassière portion having good bust supporting qualities not present in the usual types of slips;
- (h) it is economical to manufacture; and
- (i) eliminates the necessity of wearing a separate brassière.

Other objects of the invention will be set forth in the annexed description and drawing, which illustrate preferred embodiments thereof.

Fig. 1 is a perspective view of a slip disclosing the principal embodiment of the invention.

Fig. 2 is a rear elevational view of the slip illustrated in Fig. 1, shown partially broken away.

Fig. 3 is a perspective view of a modified form of brassière or bodice portion.

Fig. 4 is a sectional view on the line 4-4 of Fig. 2.

Referring to the drawing, the reference letter B designates the bodice or brassière portion of the improved slip and the letter S the skirt portion thereof. A pair of shoulder straps 11 are connected to bodice B to act as supports for the slip.

Skirt S comprises the main panel 12 and the relatively narrow longitudinal front panel or insert 13. Panel 12 is made from bias-cut fabric, that is, fabric cut at approximately an angle of 45°, while panel 13 is made from straight-cut fabric.

As shown in Fig. 4, panel 12 forms the major part of skirt S and is formed from a single piece of fabric. Said panel 12 forms the complete back or rear portion of skirt S and also a portion of the front thereof. Panel 13 is connected to panel 12 at their vertical edges by the vertical lines of stitching 14. It will be noted that the said lines of stitching 14 are located at the front of the slip, there being no seams or lines of stitching at the sides of the slip. This will give a

longer life to the slip as the seams 14 are located at a place where the tension and stress will be the least. This is true as to both the wearing and the laundering of the slip.

5 As shown in Fig. 1, panel 13 tapers outwardly as it approaches the bottom of the slip. If desired, said panel 13 may be formed of any suitable elastic material such as "Lastex," the direction of elasticity being preferably horizontal.

The upper end of panel 13 extends above the top edge of panel 12, the waistline W of the garment. The said upper portion of panel 13 extends into and forms a part of bodice B. I have designated the said upper section of panel 13 by the reference numeral 15. It will be noted that the top edge of portion 15 of panel 13 is of double concavo-convex shape.

Bodice or brassière portion B comprises section 15 of panel 13, the front bust panel 16 having a V-shaped neckline, front panels 17 and rear panel 17a. Panels 17 are identical in configuration and size. The side edges of section 15 are connected by lines of stitching to the adjacent ends of panels 17 at the front of the slip.

25 The curved top edge of section 15 is connected by a curved line of stitching to the base of panel 16. It will be noted that the lines of stitching connecting the longitudinal edges of panel 13 to the vertical edges of panel 12, the lines of 30 stitching connecting the side edges of section 15 to the sides of panels 17, and the curved line of stitching connecting the double curved top edge of section 15 to panel 16 comprises one continuous line of stitching.

35 Panel 16 of bodice B is located directly above section 15 of panel 13. The side edges of said bodice panel 16 are connected by lines of stitching to the adjacent side edges of bodice panels 17 at the front of the slip. Panels 17 are connected to the free ends of back panel 17a by the vertical lines of stitching 20 at the sides of the garment.

40 Said bodice panels 17 and 17a are connected at their bottom ends to the top end of skirt panel 12 by a circumferential line of stitching 25, thus forming the waistline W of the garment. It will be noted that the lower ends of panels 17 extend below section 15 of skirt panel 13.

In order for the slip to conform itself to the 50 back of the wearer and to make the bodice portion B form-fitting, I secure a back strap or belt member 18 within the slip, above the waistline W by means of the stitching 20. Said strap member 18 is completely concealed by the slip, it being located between the front and back por-

tions of bodice B. Strap member 18 is provided with the elastic insert 19 so as to properly accommodate and conform itself to the shape of the back of the wearer.

The principal feature of the invention is the provision of panel 13, the upper section 15 of which extends above waistline W and into bodice B, the upper end of said bodice section 15 being of double concavo-convex shape. It is this double curved shape and construction of section 15 together with bodice panels 16 and 17 that give the slip its bust supporting qualities. The curved upper portions of section 15 act as supporting means for the breast. Strap member 18 also plays a role in giving bodice B the effect of a brassière and in making the slip form-fitting. It is therefore apparent that by wearing the improved garment, the wearing of a separate brassière is obviated.

It will be noted that the improved slip is composed of a minimum number of parts. Skirt S consists of only two panels, namely, panels 12 and 13. Bodice or brassière portion B consists of front panels 16 and 17, back panel 17a, and section 15 of skirt panel 13.

The bodice embodiment in Fig. 3 is substantially the same as bodice B heretofore described. The only difference is the provision of an elastic section 15a in place of fabric section 15. However, elastic section 15a should be stretchable in a horizontal direction.

I have shown preferred embodiments of my invention, but it is obvious that numerous changes, transpositions and omissions may be made without departing from its spirit. I do not wish to be limited to specific proportions, size and configuration as to the respective panels that comprise my new and improved slip. If desired, back

strap or belt member 18 may be omitted from the improved slip without departing from the spirit of my invention.

My invention is not to be limited to a slip only, as it can readily be embodied in other undergarments and garments.

I claim:

1. A slip of the form-fitting type comprising a skirt section and a bodice, said skirt section consisting of a main panel and a longitudinal front insert panel connected to each other at the front of the slip, said main panel forming the complete rear portion of the slip and also a portion of the front thereof, the upper portion of said insert panel extending above the top edge of said main panel into the bodice and forming a part thereof, the upper end of said insert panel being of double concavo-convex shape, said bodice consisting of two similarly shaped front panels and a front bust panel located therebetween and a rear panel, said front bust panel being located above and being connected to the curved top end of the insert panel of the skirt section, said front bust panel being also connected to the front bodice panels at the front of said bodice, the bottom ends of said front and rear bodice panels being connected to the upper end of the main panel of the skirt section to form the waistline of the slip, and a back strap member connected to said bodice intermediate the front and back portions thereof.

2. A slip in accordance with claim 1 in which the material of the main panel of the skirt section is cut on the bias and the material of the insert panel of said skirt section is cut on the straight.

SYLVIA ROODNER.
